(57) **CLAIM**

The ornamental design for a vial, as shown and described.

DESCRIPTION

FIG. 1 is a perspective view of an embodiment of the vial, in a closed state;

FIG. 2 is a top plan view of the vial of FIG. 1, in a closed state;

FIG. 3 is a bottom plan view of the vial of FIG. 1, in a closed state;

FIG. 4 is a right side elevation of the vial of FIG. 1, in a closed state;

FIG. 5 is a front elevation of the vial of FIG. 1, in a closed state;

FIG. 6 is a left side elevation of the vial of FIG. 1, in a closed state;

FIG. 7 is a rear elevation of the vial of FIG. 1, in a closed state;

FIG. 8 is a perspective view of the vial of FIG. 1, in an opened state;

FIG. 9 is a top plan view of the vial of FIG. 1, in an opened state;

FIG. 10 is a bottom plan view of the vial of FIG. 1, in an opened state;

FIG. 11 is a right side elevation of the vial of FIG. 1, in an opened state;

FIG. 12 is a front elevation of the vial of FIG. 1, in an opened state;

FIG. 13 is a left side elevation of the vial of FIG. 1, in an opened state; and,

FIG. 14 is a rear elevation of the vial of FIG. 1, in an opened state.

In FIGS. 8 and 9, the broken lines immediately adjacent the shaded areas represent the bounds of the claim, and other broken lines are included for the purpose of illustrating a portion of the vial that forms no part of the claimed design. None of the broken lines form a part of the claimed design.
